(57) **CLAIM**

The ornamental design for a playground apparatus as shown and described.

DESCRIPTION

FIG. 1 is a perspective view of a playground apparatus showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

A bottom of the playground apparatus is not visible during use and is thus unornamented. As such, a bottom view is omitted and forms no part of the claimed design.
